UNITED STATES PATENT OFFICE

115,524

DESIGN FOR A MOLDED PULP PLATE OR THE LIKE

Walter H. Randall, Waterville, Maine, assignor,
by mesne assignments, to The Canal National
Bank of Portland, Portland, Maine, a national
banking association, as trustee

Application December 21, 1938, Serial No. 81,935

Term of patent 14 years

To all whom it may concern:

Be it known that I, Walter H. Randall, a citizen of the United States, residing at Waterville, in the county of Kennebec, State of Maine, have invented a new, original, and ornamental Design for a Molded Pulp Plate or the like, of which the following is a specification, reference being had to the accompanying drawing, forming part thereof.

Fig. 1 is a side elevational view of a molded pulp plate or the like showing my new design.

Fig. 2 is a bottom plan view thereof, and

Fig. 3 is a sectional view on the line 3—3, of Fig. 2.

The characteristic feature of the design resides in the series of spaced raised ribs on the outer surface of the side and bottom walls of the plate, having the particular configuration and appearance as shown, the inner surface of the side and bottom walls of the plate being smooth.

I claim:

The ornamental design for a molded pulp plate or the like, as shown and described.

WALTER H. RANDALL.
